UNITED STATES PATENT OFFICE.

LESLIE ELTON BROWNLEY, OF UNION HILL, NEW JERSEY.

PROCESS FOR MAKING COMBINED REAL-LIFE AND ANIMATED-CARTOON MOTION-PICTURES.

1,355,648.

Specification of Letters Patent.

Patented Oct. 12, 1920.

Application filed November 7, 1917. Serial No. 200,716.

To all whom it may concern:

Be it known that I, LESLIE ELTON BROWNLEY, a citizen of the United States, residing at Union Hill, in the county of Hudson and State of New Jersey, have invented certain new and useful Improvements in Processes for Making Combined Real-Life and Animated-Cartoon Motion-Pictures, of which the following is a specification.

10 The object of this invention is to provide an improved process for producing a combination of animated comic characters or cartoons and photographic backgrounds, or so-called real life action, upon motion picture films.

Another object of this invention comprises the process of producing real life action in combination with animated silhouette figures, this latter process comprising a part 20 of the first process above referred to.

And a still further object of the invention is to provide an improved combination and sequence of novel steps in the manufacture of motion picture film, comprising the combination of real life action and animated cartoon comic characters of such nature that the necessity of making photographic enlargements of the individual exposures upon a reel is eliminated, and the cost of production 30 is thereby decreased to a minimum.

Further objects and details in the improved process, above referred to, are fully described in the following specification when read in conjunction with the accompanying drawings, in which Figure 1 is a negative photograph of real life action; Fig. 2 is a positive print of the negative of Fig. 1, but intended to represent such a print in undeveloped form; Fig. 3 is a cartoon character 40 in detail upon a black background; Fig. 4 is a black silhouette of the cartoon of Fig. 3 without detail; Fig. 5 is a negative print of Fig. 4; Fig. 6 is a negative print formed as the result of reëxposing the positive print 45 of Fig. 2 in undeveloped condition to light with the silhouette screen of Fig. 5 superimposed thereupon, and then developing and printing this composite print; Fig. 7 is a negative obtained by photographing Fig. 3 showing all details of the comic character; and Fig. 8 is a positive print of the negative print and cartoon silhouette combination 50 of Fig. 6, with the detailed cartoon character of Fig. 7 superimposed thereupon.

55 Referring to the drawings, negative ex-

posures on a motion picture film are produced and developed such as that represented by the scene in Fig. 1, this being understood to represent real life action solely. From this negative a print is made which is obviously positive in character and represented by Fig. 2, though it is to be understood that at this stage of the process said positive print is left undeveloped.

Each of the exposures of the negative film, as represented by Fig. 1, is then projected in enlarged proportions upon a ground glass or other suitable surface, upon the reverse side of which in the case of glass an artist can readily draw upon a sheet of suitable material a comic or cartoon character of the kind, position and arrangement desired to finally appear in combination with the scene represented by the particular exposure being thus enlarged. Having thus drawn the desired character in detail upon the said sheet of material, the background is filled in to make the same black as in Fig. 3. Or this step can be obtained by tracing the drawing upon celluloid and opaquin back of character, then superimposing said celluloid sheet upon a black, red, or other suitably colored surface. This comic character with black background is then reproduced by tracing the same upon a white sheet of paper, or upon celluloid and the character blackened on the reverse side, as indicated in Fig. 4, the same comprising a black silhouette character upon a white background.

Having thus obtained the arrangement illustrated by Fig. 4, the same is photographed by means of one or more exposures upon a negative motion picture film, the result being exactly as represented by Fig. 5. At this stage of the process the film, represented by Fig. 5, after being developed, is superimposed in exact register upon the undeveloped film represented by Fig. 2, and the combined films run through a camera or printing machine, as may be found most desirable, and the said film of Fig. 2 again exposed to light. When this is completed, the film of Fig. 2 is developed and will be found to comprise the combination of real life action with the comic character in black silhouette thereupon and in exact registry therewith, from which a negative is made, the same represented by Fig. 6.

A succession of negative photographs is

then made of the cartoons, as shown in Fig. 3, with all of their detail present, the result being an arrangement such as is shown in Fig. 7, the detailed cartoon being surrounded by a transparent background. After this is developed, the same is superimposed upon the negative illustrated by Fig. 6, and a positive print of the two combined is then made, with the result shown in Fig. 8 after development, the same comprising a positive print of real life action in combination with a cartoon character having all of the desired details.

A somewhat modified form of motion picture production can be obtained by producing a positive print of the real life action, shown in Fig. 1, in combination with a black silhouette figure such as that shown in Fig. 4, as described in the second preceding paragraph, or as follows. This is accomplished very easily after obtaining the negative exposure, shown in Fig. 6, with the comic character combined therewith in white silhouette. Having such a combination negative a positive is made therefrom in the usual printing machine and after development the resulting product will be found to be like the arrangement shown in Fig. 8, except that the comic character is a black silhouette throughout all of its movements or changes in position, instead of having the details as hereinbefore described in the first process of which this latter forms in a way but a part.

Having thus described my invention, what I claim and desire to protect by Letters Patent of the United States is:

1. The process of producing a motion picture product comprising the following steps:—photographing a real life scene, making a positive print of the negative produced, making a comic character, making a black silhouette character from said first character, photographing said black silhouette character to form a white silhouette character with a black background, making a

negative of said comic character, superimposing said white silhouette character upon the positive print before development and then exposing the same to light, developing said positive print, making a negative from said last-named print, and then combining said negative with the negative of said comic character and printing and developing said combination to form the final print. 55

2. The process of producing a motion picture product comprising the following steps:—photographing a real life scene, making two positive prints of the negative produced, projecting one of said prints after development upon a surface, making a comic character upon said surface in enlarged form to correspond with said projection, making a black silhouette character from said first character, photographing said silhouette character to form a white silhouette character upon a black background, making a negative of said comic character, superimposing said white silhouette character upon the other positive print before development 70 and again exposing the same to light, developing said latter positive print, making a negative from said last-named print, and then combining said negative with the negative of said comic character and printing 75 said combination to form the final positive print.

3. The process of producing a motion picture product comprising the following steps:—photographing a real life scene, 80 making a positive print of the negative produced, making a black silhouette character, photographing said silhouette character to form a white silhouette character with a black background, superimposing said white 85 silhouette character upon the positive print before development and again exposing the same to light, and developing said print.

In testimony whereof I have affixed my signature.

LESLIE ELTON BROWNLEY.
